UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 17,850, dated November 1, 1887.

Application filed September 21, 1887. Serial No. 250,345. Term of patent 3½ years.

To all whom it may concern:

Be it known that I, ETTA L. JENKINS, of the city, county, and State of New York, have invented and produced a new and original Design for a Pattern of a Miss's Costume; and I do hereby declare that the engraved prints accompanying this specification convey to any one accustomed to using paper patterns a clear understanding of how a garment made up by the pattern will appear.

The design shows a round walking-skirt and a close-fitting basque. The skirt displays a front drapery that falls in two box-plaits nearly to the edge at the left side, and inside plaits that flare at the center of the front and exhibit a high draping by plaits at the left side, and a back drapery that falls in kilt-plaits at the left side nearly to the edge and displays

bourne loops at the top and a high draping at the right side. The basque exhibits under-folded plaits below the waist-line of its center seam, plaited surplices upon the front, the left surplice disappearing beneath the right surplice, which crosses diagonally to the left side, coat-sleeves, and a standing collar. The outline of the basque is rounding at the front and sides and deepens at the center of the back. 20 25

What I claim as my invention, and desire to secure by Letters Patent, is—

The design for a miss's costume, as shown 30 in the engraved prints accompanying this specification.

ETTA L. JENKINS.
